UNITED STATES PATENT OFFICE.

RALPH TILLES, OF NEW YORK, N. Y.

CARPENTER'S PLANE.

965,766.

Specification of Letters Patent. Patented July 26, 1910.

Application filed April 8, 1910. Serial No. 554,188.

To all whom it may concern:

Be it known that I, RALPH TILLES, a subject of the King of Great Britain, and residing at New York, in the county of New York and State of New York, have invented certain new and useful Improvements in Carpenters' Planes, of which the following is a specification, such as will enable those skilled in the art to which it appertains to make and use the same.

This invention relates to carpenters' planes, and the object thereof is to construct a tool of this class in such manner as to enable the plane to clear itself in use or operation under varying conditions; and with this and other objects in view the invention consists in a carpenter's plane constructed as hereinafter described and claimed.

The invention is fully disclosed in the following specification, of which the accompanying drawing forms a part, in which the separate parts of my improvement are designated by suitable reference characters in each of the views, and in which—

Figure 1 is a longitudinal central sectional view of a carpenter's plane made according to my invention, the section being taken on the line $x-x$ of Fig. 2; Fig. 2 a transverse section on the line $y-y$ of Fig. 1; Fig. 3 a detail view showing a part of the construction detached from the body of the plane, and showing a part in section; Fig. 4 a side view of another detail of the construction detached, and Fig. 5 a view similar to Fig. 4 but at right angles thereto.

In the drawing forming part of this specification I have shown at a an ordinary carpenter's plane of the class specified, comprising a block a^2 , in the top portion of which is a recess a^3 which opens downwardly through the bottom of said block to form the usual transverse opening a^4 , and the rear wall of the recess a^3 is inclined downwardly and forwardly in the usual manner and mounted therein is the usual cutting blade b , the edge b^2 of which extends into and through the transverse aperture a^4 , and the outer end portion b^3 of said blade is provided with a longitudinal slot b^4 , and placed on the top front surface of said blade is a plate b^5 , which is secured to and made adjustable on the blade b by means of a set screw b^6 passed through the slot b^4 , and the plate b^5 is provided with a beveled edge b^7 which bears on the top surface of the edge portion b^2 of the blade b in the usual manner,

and the blade b and plate b^5 are adjustable in the block a^2 and are held therein by a wedge member b^8 , all these parts being of the usual or any preferred construction.

The bottom surface of the front end portion a^5 of the block a^2 is provided with a rectangular recess a^9 , in which is placed a supplemental block c , the bottom surface of which is flush with the bottom surface of the block a^2 , and this block c is made adjustable toward and from the cutting edge of the blade b so as to regulate the dimensions of said aperture a^4 in front of the cutting edge of said blade, in order to enable the plane to clear itself when in use, and this block together with the means employed for adjusting it into different position constitutes the subject matter of this invention.

The front end portion a^5 of the block a^2 is provided centrally thereof with a vertically arranged chamber d , which opens downwardly and secured in the central top surface of the block c is a screw e having a head e^2 , to which is hinged a bolt member f , the connection between said bolt member and the head e^2 of the screw e as shown at f^2 , being such that said bolt member is free to swing forwardly and backwardly.

The upper end portion f^3 of the bolt member f is screw threaded as shown at f^4 , and the lower end portion thereof is enlarged and the opposite side portions thereof flattened as shown at f^5 , and formed in the top part of the lower end portion of the bolt member f is a transverse aperture f^6 which ranges forwardly and backwardly and is provided with a downwardly directed extension f^7 .

The front end portion a^5 of the block a^2 is also provided centrally thereof with a forwardly and backwardly ranging bore a^7 , provided with a rear end extension a^8 in the back wall of the chamber d , and mounted in said bore is a forwardly and backwardly movable bolt g , the front end portion of which is screw threaded as shown at g^2 , and the rear end portion of which is enlarged as shown at g^3 , and the enlarged part g^3 of the bolt g is cut away transversely to form a flat head g^4 and transverse recesses g^5 which form a flat neck g^6 by which the head g^4 is connected with the enlarged portion g^3 of said bolt, and the side walls of the transverse recesses g^5 , in the form of construction shown, are beveled as shown at g^8 .

The outer end portions of the bolt g is

provided with a thumb nut h , and the upper end portion of the bolt f is provided with a thumb nut h^2 , and in practice, in order to assemble the parts c , f and g the bolt f is connected with the block c and passed upwardly through the chamber d until the aperture f^6 in the enlarged lower end portion of the bolt f registers with the bore a^7 . The enlarged end portion g^8 of the bolt g is then 10 passed backwardly through the bore a^7 , and the head g^4 of the part g^3 of the bolt g passes through the aperture f^6 , at which time the bolt f and block c are moved upwardly until said block c is firmly seated as 15 shown in Figs. 1 and 2, and in this operation the neck g^6 of the enlarged part g^3 of the bolt g passes downwardly into the downwardly directed extention f^7 of the aperture f^6 in the bolt f , and said bolts f and g are 20 locked together, and by turning the nut h the block c may be moved forwardly or backwardly according to the direction in which said nut is turned, and this operation, as will be understood, enlarges or diminishes 25 the aperture a^4 in front of the cutting edge b^2 of the blade b and said block c may be locked in any desired position by means of a nut h^2 .

It will be understood that the nut h must 30 be loosened in order to adjust the block c as above described and when said block c has been adjusted in the desired position the nut h^2 is again tightened.

The above described operation depends on 35 the hinge connection of the bolt f with the block c , and the method of connecting the bolt g with the bolt f but my invention, as will be understood, is not limited to the exact means herein shown and described for 40 making these connections, and various

changes in and modifications of the construction described may be made, within the scope of the appended claim, without departing from the spirit of my invention or sacrificing its advantages.

Having fully described my invention, what I claim as new, and desire to secure by Letters Patent, is—

A carpenter's plane comprising a main block, the top portion of which is provided with a recess which opens downwardly through the bottom surface of said block to form a transverse aperture, the front end portion of said main block being provided in the bottom thereof with a recess in which is mounted a supplemental block, and means for adjusting said supplemental block toward and from said aperture consisting of a bolt having a hinge connection with the supplemental block and passing upwardly 50 through the main block and provided at its upper end with a nut, another bolt movable forwardly and backwardly through a bore in the front end of the main block and adapted to be detachably and loosely connected with the first named bolt, said supplemental bolt being provided at its outer end with a nut and said main block being provided with a chamber in which the lower end of the first named bolt is movable forwardly and backwardly.

In testimony that I claim the foregoing as my invention I have signed my name in presence of the subscribing witnesses this 6th day of April 1910.

RALPH TILLES.
